Specification for Design.

Patented Mar. 9, 1920.

Application filed January 10, 1919. Serial No. 270,603. Term of patent 7 years.

To all whom it may concern:

Be it known that I, JOHN C. McLEAN, a citizen of the United States, residing at 1491 Waterbury road, Lakewood, Cuyahoga county, Ohio, have invented a new, original, and ornamental Design for Tires, of which the following is a specification, reference being had to the accompanying drawings, forming a part thereof.

In the drawings, Figure 1 is a section, and Fig. 2 is a top plan view showing my new design.

I claim:

The ornamental design for a tire substantially as shown.

JOHN C. McLEAN.
